Clarance M. Mendenhall

BY

Francis J. Chamberlain
his ATTORNEY.

UNITED STATES PATENT OFFICE.

CLARENCE M. MENDENHALL, OF NEW ROCHELLE, NEW YORK.

WATER-GAGE GLASSES.

1,197,300.

Specification of Letters Patent.

Patented Sept. 5, 1916.

Application filed March 3, 1910. Serial No. 547,011.

To all whom it may concern:

Be it known that I, CLARENCE M. MENDENHALL, a citizen of the United States of America, residing in New Rochelle, in the county of Westchester, in the State of New York, have invented certain new and useful Improvements in Water-Gage Glasses, of which the following is a true and exact description, reference being had to the accompanying drawings, which form a part thereof.

My invention relates to the construction of water gages and has for its object to provide a strong, durable and inexpensive water gage for boilers and one in which the water line will be strongly marked and visible through a wide arc in front of the glass.

My invention consists in part in a novel form of bull's-eye glass chiefly marked by the formation of the inner face of the bull's-eye into a series of parallel prisms and also in the formation of the bull's-eye with a portion adapted to engage with and lock into the portion of the casing in which it is seated so as to prevent rotation of the glass.

Further, my invention consists in the features of construction of a gage adapted to be used in connection with bull's-eye glasses which features will be best understood as described in connection with the drawings in which my invention is illustrated and in which—

Figure 1 is a front elevation of a water gage adapted for use with a plurality of my improved bull's-eye sight glasses, one of the latter being removed from the gage. Fig. 2 a cross-section on the line 2—2 of Fig. 2. Fig. 3 a longitudinal section on the line 3—3 of Fig. 1, but showing the bull's-eye removed in Fig. 1. Fig. 4 is a front elevation of an improved and preferred form of gage casing adapted for use with bull's-eye glasses and having novel features of construction which form a part of my invention. Fig. 5 is a cross-section on the irregular line 5—5 of Fig. 4, and Fig. 6 a view of the inner face of my improved bull's-eye in its preferred form.

A, Figs. 1 2 and 3 is a water gage casing, having openings B and B' at its ends by which it is connected to the boiler and an internal chamber B², and having through the case of the casing a series of apertures C C, etc., adapted for the reception and securing in place of a series of bull's-eye sight glasses. The apertures are externally

of circular outline and are formed first with an internally threaded portion C' within which lies the non-threaded cylindrical portion C² terminating in an inwardly extending flange C³ which forms a seat for the bull's-eye glass and through which extends an opening C⁴ which, as shown, and as I prefer to construct it, is of non-circular section. D, D, etc., are the bull's-eye sight glasses, the outer portion of which is of cylindrical form, as shown at D', terminating in a convex face, as shown at D². Near the inner face of the bull's-eye an outwardly extending flange D³ is formed which fits into the cylindrical portion C² of the aperture C and rests upon the flange or face C³. The inner face D⁴ of the bull's-eye is formed into a series of parallel prisms and is, as shown, of a form which will project and fit into the inner apertures C⁴ so as to interlock therewith and prevent rotation of the bull's-eye in its seat, the prisms being formed so that when the glass is in place in the casing and the casing in position for use the prisms will lie vertically. Each bull's-eye D is anchored in place in the assembled gage by a corresponding externally threaded ring F screwed into the outer threaded portion of the corresponding socket C'. A packing washer E is interposed between each ring F and the corresponding bull's-eye D.

While I believe the construction shown and described to be the best for the purposes I have in view it is obvious that the interlocking of the bull's-eye glass with its seat in the casing so as to prevent rotation of the glass in the casing can be effected by any interengaging or interlocking of the glass with the casing.

A', Figs. 4 and 5, shows an improved and preferred form of sight glass casing having, as in the case of the casing A, top and bottom apertures as B and B' for connection with the boiler, these apertures connecting the chambers B² and B⁴, each of which chambers is formed with a series of sight glass apertures, one series indicated at C', C', C'. These apertures are constructed in the same way as those already described in connection with the casing A and the two series are formed at an acute angle to each other for the double purpose of bringing both series within the clear view of a person standing in front of the glass, while, at the same time, greatly increasing the arc of visibility through which either one or the

other series can be seen. The apertures of the two series are staggered with respect to each other as shown, and so formed and arranged that the water level in the internal 5 chambers of the casing will always be visible through one or more of the bull's-eye glasses. The bull's-eye glasses used in the casing A' are identical with those used in casing A.

10 Having now described my invention, what I claim as new and desire to secure by Letters Patent is—

1. A bull's-eye sight glass for a water gage having a substantially circular cross-section and an inner face formed into a series of parallel vertical prisms.
2. A bull's-eye sight glass for a water gage having a substantially circular cross-section with a portion of its configuration 20 departing from circular outline and adapted to fit and lock with a non-circular section of the frame of a gage in which it is to be set, and provided with an inner face formed into a series of parallel vertical prisms.
- 25 3. A bull's-eye sight glass for a water gage having a flange D² adapted to rest upon the gage casing and an inwardly projecting face of non-circular outline formed into a series of parallel prisms.
- 30 4. A water gage consisting of a metallic casing adapted to be connected to a boiler at the top and bottom and having two rows of sight holes extending through the casing at an acute angle to each other and so that both 35 sets are visible at the same time from the front of the frame, the sight holes of one row being formed in staggered relation to and overlapping those of the other and so disposed in the frame that the water line in
- 40 the casing is always visible through one or more of the staggered holes, in combination with bull's-eye sight glasses set in said sight holes.

5. A water gage consisting of a metallic casing adapted to be connected to a boiler at 45 the top and bottom and having two rows of sight holes extending through the casing at an acute angle to each other and so that both sets are visible at the same time from the front of the frame, the sight holes of one 50 row being formed in staggered relation to and overlapping those of the other and so disposed in the frame that the water line in the casing is always visible through one or more of the staggered holes in combination 55 with bull's-eye sight glasses set in said sight holes and having their inner faces formed into a series of parallel vertical prisms.

6. A water gage consisting of a metallic casing adapted to be connected to a boiler at 60 the top and bottom and having two rows of sight holes extending through the casing at an acute angle to each other and so that both sets are visible at the same time in front of the frame, the sight holes of one row being 65 formed in staggered relation to and overlapping those of the other and so disposed in the frame that the water line in the casing is always visible through one or more of the staggered holes, said sight holes having 70 an outer substantially circular section with a seat at its bottom and a noncircular opening through said seat, in combination with bull's-eye sight glasses having substantially 75 circular sections adapted to extend into the circular sections of the sight openings, flanges adapted to rest on the seats and noncircular rearward extensions adapted to extend and fit into the noncircular openings through the seats, said noncircular portions 80 having a series of parallel vertical prisms formed on them.

CLARENCE M. MENDENHALL.
